UNITED STATES PATENT OFFICE.

JOHN ALPINE, OF STEVENS POINT, WISCONSIN.

FOURDRINIER MACHINE.

1,275,826.

Specification of Letters Patent. Patented Aug. 13, 1918.

Application filed June 2, 1917. Serial No. 172,395.

To all whom it may concern:

Be it known that I, JOHN ALPINE, a citizen of the United States, residing at the city of Stevens Point, county of Portage, 5 and State of Wisconsin, have invented new and useful Improvements in Fourdrinier Machines, of which the following is a specification.

My invention relates to improvements in 10 Fourdrinier machines.

The object of my invention is to provide improved means for adjusting the inclination of the initial wire conveyer in accordance with the stock, whereby the inclination of the wire cloth may be varied without readjusting or interfering in any way with the feeding means, the breast roll remaining at a uniform height, whereas the couch rolls are lifted or lowered to vary the inclination 20 of the cloth. It is difficult to regulate the feed of the stock where the breast roll is raised or lowered, thereby supporting the initial or receiving end of the wire cloth at varying levels with reference to the reservoir 25 from which the stock is delivered, but it has heretofore been deemed necessary to do this for the reason that it was assumed to be impossible to adjust the couch roll without varying the distance between the apron and 30 the suction boxes, and between the couch roll and the take off conveyer. My invention contemplates mounting the suction boxes, guide roll, couch roll and take off roll upon an adjustable platform which may be raised, 35 and lowered and the inclination of which may be varied as desired to suit the requirements of the work, without varying the relation of these elements to each other. In this manner, I am enabled to employ a set of jack 40 screws which can be quickly adjusted to the desired position in accordance with the requirements of the stock and without affecting the operation of the machine in any way except to vary the rate of flow of the 45 stock along the initial portion of the wire cloth in so far as such flow is due to gravity and therefore affected by the variation in the inclination of the cloth.

In the drawings—
50 Figure 1 is a side elevation of the front

end of a Fourdrinier machine showing the receiving and discharge portions of the initial conveyer, the central portion of said conveyer being broken away.

Fig. 2 is a side elevation of the driving 55 mechanism and also the couch roll.

Fig. 3 is a rear end elevation of the platform and its associated parts in elevated position.

Like parts are identified by the same reference characters throughout the several views.

The stock is fed from a vat 1 in the usual manner and is permitted to flow along the apron 2 to the breast roller 3, around which 65 the wire cloth 4 passes at its receiving end. The wire cloth is of ordinary construction and receives the stock from the vat 1 in any ordinary manner, the apron 2 being illustrated conventionally as representing 70 any suitable means for feeding the stock to the roller.

The platform 5 is pivotally connected at 7 75 with any suitable support, such for example as the posts 8.

Jack screws 11 and 12 support the platform at its rear end and preferably at intermediate points, these jack screws having screw threaded bearings in bed blocks 13, whereby the platform 5 may be swung about 80 its pivotal axis at 7. Each of the jack screws is provided with a swiveled, or preferably universally jointed, head piece 15, which may, if desired, be permitted to slide on the under surface of the platform to 85 avoid cramping when the position of the platform is changed. A sliding movement of the members 15 along the platform 5 is, however, hardly necessary, as the arc in which the platform swings at the points 90 where the jack screws are located, has very slight curvature, and if the members 15 are loosely articulated with the upper ends of the screws, ordinary adjustments may be 95 made without cramping effects.

The frame 17 which supports the suction boxes 18 and the idler rollers 19, over which the wire apron extends, is supported by a set of standards 21 and 22, the latter being 100 provided with a bracket 24 which supports

the guide roll 25. Couch roll 27 is also supported from the platform 5 by standards 29. The final suction box 31, over which the initial portion of the first felt conveyer 32 5 travels after passing the take-off roller 34 is mounted upon bars 35 hung upon the roller shafts 36 and 37 respectively. The felt conveyer 32 extends over a guide roll 40 on its return side and around a set of tension rollers 41 and 42, these rollers being so located that the take off roller 34 may be raised or lowered without materially varying the tension of the conveyer.

Initial compression roller or top couch 15 roll 45 is supported from standards 22 by swinging arms 46 of ordinary construction. The compression is regulated by levers 47 (one at each end) and links 48. These parts are of ordinary construction, except that 20 they are supported from the adjustable platform 5, and therefore require no further description.

Couch roll 27 is positively driven from a shaft 50 through sprocket wheel 51, chain 25 52, and a sprocket wheel 53 mounted on the couch roll shaft 54. Shaft 50 is journaled in suitable standards 56 mounted on the bed 9, said standards supporting the shaft at a level above the couch roll when the latter 30 is depressed and below the couch roll when the latter is raised to the limit of its upward adjustment.

Within the range of the desired vertical adjustment of the couch roll, it is not necessary to vary the length of sprocket chain 52 in order to drive the couch roll in any of its positions of adjustment, the chain being a little slack when the couch roll is at the limit of its adjusting movement in either 40 direction, and not too tight in the intermediate positions.

With the construction above described and as illustrated in the drawings, platform 5 may be lowered at its rear end until it is brought into close proximity to the bed 9, thereby providing an extreme downward inclination of the wire with a consequent rapid flow of the stock along the initial portion of the wire. When the condition of the stock 50 requires a slower flow, it is merely necessary to actuate the jack screws 11 and 12 to raise the platform 5 at its rear end, the front end remaining permanently at the same level as fixed by the pivot rod 7. Therefore the elevation of the rear end of the platform 5 varies the inclination of the wire without varying the relation of the suction boxes, guide roll, couch rolls and initial compression roll 45, all of these being supported 55 from the platform as above explained.

The take off roller 34 of the felt conveyer is also supported from platform 5, this roller being journaled in suitable supports 60 car-

ried by bracket 30. It will be observed that, as the roller 34 moves upwardly toward the position indicated by dotted lines in Fig. 1, the distance is shortened between it and guide roller 62, but the distance is correspondingly lengthened between roller 34 and tension roller 42, whereby the tension of the 70 conveyer is maintained. The tension of the wire will, of course, remain the same under all adjustments, there being no variation in the distance between the breast roll 3 and couch roll 27. Suction box 31 moves upwardly or 75 downwardly in correspondence with the movement of the portion of the felt conveyer under which it is supported, and therefore no other adjustment is required.

When platform 5 is raised, at its rear end, 80 from the position in which it is illustrated in Fig. 1 toward the position indicated by dotted lines in said figure, it is obvious that the breast roll 3 will swing slightly to the right in the direction of the vat 1. The apron 2 may therefore be made longitudinally adjustable in order that its delivery end may be held in uniform proximity to the breast roll, but in the construction illustrated, this will not be necessary, as the apron board 2' is sufficiently spaced from the breast roll to permit the slight required movement of the latter.

I claim—

1. In a Fourdrinier machine, the combination with the wire cloth apron, and a set of rollers over which said apron travels, of a relatively fixed bed, a support pivotally connected with the bed at the receiving end of the machine, and adjustably connected with the bed at other points, whereby its rear end may be raised and lowered, a set of couch rolls carried by the rear end of said support and between which said wire cloth travels, and supporting bearings for said rollers carried by said support.

2. In a Fourdrinier machine, the combination with the pulp receiving cloth, of a support for the cloth pivoted on a horizontal axis underneath the breast roll, the receiving end of said cloth at a substantially permanent elevation with reference to the source of pulp supply, means for raising and lowering the rear end of said support and proportionally raising all intermediate portions of the cloth on the pulp carrying side to vary the inclination of the pulp carrying portion thereof.

3. In a Fourdrinier machine, the combination with a pulp feeding device, of a breast roll in substantially fixed relation to the pulp feeding device, a vertically adjustable couch roll, a couch roll support pivoted to swing upwardly and downwardly about an axis underneath the breast roll, a set of intermediate rolls and means for supporting

them from the couch roll support, whereby all of the rolls may be simultaneously adjusted to an extent proportional to their distance from the breast roll, and a pulp carrying wire cloth extending in the form of an endless belt around said rollers.

4. In a Fourdrinier machine, the combination of a pulp feeding device, a breast roll at the discharge end of said device, a vertically adjustable couch roll, a set of suction boxes interposed between the couch roll and the breast roll, a pulp carrying apron extending in the form of an endless belt around said rollers and over the suction boxes, a platform pivotally supported at one end underneath the breast roll and adapted to be raised and lowered at the other end, and means for supporting a couch roll and suction boxes from said platform, whereby both the suction boxes and the couch roll may be raised or lowered in direct proportion to their distance from the breast roll by an adjustment of the swinging end of the platform.

5. In a Fourdrinier machine, the combination with pulp feeding devices, a bed, a platform pivoted to the bed at its front end, a pulp receiving cloth supported from said platform, and means for raising and lowering the platform in a swinging movement upon its said pivotal connection with the bed, together with a suction box supported from said platform in associated relation to the receiving portion of the take off conveyor, and means for tilting the said suction box to keep its upper surface parallel with the conveyer in various positions of platform adjustment.

6. In a Fourdrinier machine, the combination with an initial pulp receiving cloth, a vertically adjustable roller supporting the rear end of said cloth and over which said cloth travels, a take off carrier, and a vertically adjustable take off roller over which said take off carrier travels at its receiving end, said rollers being located parallel to and in proximity to each other.

7. In a Fourdrinier machine, the combination with a pulp receiving cloth, a vertically adjustable roller supporting the discharge end of said cloth and over which the cloth passes, a vertically adjustable take off roller parallel to and in proximity to the first mentioned roller, a set of tension rollers mounted in relatively fixed supports, a take off carrier extending around said tension rollers and the take off rollers.

8. In a Fourdrinier machine, the combination with a pulp receiving cloth, a vertically adjustable roller supporting the discharge end underneath the breast roll of said cloth and over which the cloth passes, a vertically adjustable take off roller parallel

to and in proximity to the first mentioned roller, a set of tension rollers mounted in relatively fixed supports, a take off carrier extending around said tension rollers and the take off rollers, one of said rollers being located near the vertical plane of the take off roller and the other of said tension rollers being located rearwardly therefrom, whereby the take off roller may be raised and lowered without materially varying the tension of the take off carrier.

9. In a Fourdrinier machine, the combination with a bed, of a platform pivotally connected with the bed, a breast roll supported from the pivoted end of the platform, a couch roll supported from the platform distant from its pivoted end, a set of suction boxes also supported from the platform between said rolls, another suction box supported from the platform beyond the couch roll, a take off roll supported from the platform between the couch roll and said last mentioned suction box, a pulp receiving cloth arranged to travel over the breast roll, the first mentioned suction box and couch roll, and a take off carrier arranged to travel over the take off roll and the suction box with which said roll is associated, and means for raising and lowering the end of the platform distant from its pivotal connection with the bed.

10. In a Fourdrinier machine, the combination with a bed, of a platform pivotally connected with the bed, a breast roll supported from the pivoted end of the platform, a couch roll supported from the platform distant from its pivoted end, a set of suction boxes also supported from the platform between said rolls, another suction box supported from the platform beyond the couch roll, a take off roll supported from the platform between the couch roll and said last mentioned suction box, a pulp receiving cloth arranged to travel over the breast roll, the first mentioned suction box and couch roll, and a take off carrier arranged to travel over the take off roll and the suction box with which said roll is associated, and means for raising and lowering the end of the platform distant from its pivotal connection with the bed.

11. In a Fourdrinier machine provided with an initial pulp carrier, and means for raising and lowering the same at its rear end, the combination with such carrier of a take off carrier, means for raising and low-

ering the initial portion thereof in correspondence with the adjustment of the other carrier, a suction box for the take off carrier, means for raising and lowering the suction box, and means for tilting the same.

12. In a Fourdrinier machine the combination with a carrier having an inclined carrying portion, means for raising the inclined carrying portion at one end, an independently supported suction box, means for raising and lowering the same, and means for

tilting the suction box on an axis transverse to the carrier, whereby its upper surface may be kept parallel to the carrier in the various positions of carrier adjustment. 15

In testimony whereof I affix my signature in the presence of two witnesses.

JOHN ALPINE.
